(57) CLAIM

The ornamental design for a brush, as shown and described.

DESCRIPTION

FIG. 1 is a top, front isometric view of a brush showing our new design.

FIGS. 2 and 3 are top and bottom views, respectively, of the embodiment of FIG. 1.

FIGS. 4 and 5 are left and right side views, respectively, of the embodiment of FIG. 1; and,

FIGS. 6 and 7 are front and rear views, respectively, of the embodiment of FIG. 1.

The present invention relates in general to a cooking utensil and, in particular, to a grilling utensil.
